Fig. 3

FIG. 1 is a perspective view of a stringed musical instrument, specifically a plucked Ukrainian bzura, bzura or kobzura of the colascione class or long necked lute showing my new design;

FIG. 2 is a fragmentary perspective view showing the peghead from a different direction;

FIG. 3 is a face view; and

FIG. 4 is a fragmentary left side elevational view thereof.

Portions of the drawing figures are shaded to indicate contrast in appearance. The strings have been omitted from FIG. 4 for convenience in illustration.

I claim:

The ornamental design for a stringed musical instrument, as shown and described.
